Primary Examiner — Joseph Kukella*Assistant Examiner* — Darryl J Dardenne(74) *Attorney, Agent, or Firm* — Bridgeway IP Law Group, PLLC; Jihun Kim; Hyun Woo Shin(57) **CLAIM**

The ornamental design for a cup holder, as shown and described.

DESCRIPTION

FIG. 1 is a front perspective view of a cup holder showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof; and,

FIG. 9 is another front perspective view of the cup holder shown in a configuration of use.

The broken lines throughout the drawing figures depict portions of the cup holder that form no part of the claimed design. The broken lines and regions bounded by broken lines form no part of the claimed design.
